UNITED STATES PATENT OFFICE.

ETHELBERT L. BARNES, OF PORTLAND, OREGON.

WOODWORKING-MACHINE.

1,120,120.

Specification of Letters Patent.

Patented Dec. 8, 1914.

Application filed February 16, 1914. Serial No. 818,886.

To all whom it may concern:

Be it known that I, ETHELBERT L. BARNES, a citizen of the United States, residing in Portland, in the county of Multnomah and 5 State of Oregon, have invented certain new and useful Improvements in Woodworking-Machines, of which the following is a specification.

My invention relates to woodworking machines adapted to finish wood-products into their desired form and more particularly to automatic machines for producing cross-arms for telephone and telegraph poles, and has for its object to provide a machine of 10 the character described, adapted to automatically chamfer or round off the weather-edge of cross-arms in such manner as to leave an unchamfered intermediate portion formed to fit a transverse notch in a telephone pole. I also provide novel means for 15 adjusting my machine for cross-arms of various linear and transverse dimensions.

What constitutes my invention will be 20 hereinafter specified in detail and succinctly 25 set forth in the appended claims.

The novel features of my cross-arm shaper are fully illustrated in the accompanying drawings, in which—

Figure 1 is a plan view of the cross-arm shaper and attendant conveyers and shows a cross-arm with its forward end partially chamfered. Fig. 2 is a front elevation of the machine with a portion of the cutter-carrier removed so as to show more clearly 30 the drive-gears for operating the live-rolls. Fig. 3 is a side elevation of the machine. Fig. 4 is a chamfered cross-arm in elevation. Fig. 5 is an end elevation of the cross-arm shown in Fig. 4 and shows more clearly 35 the manner in which it is chamfered. Fig. 6 is a detail sectional elevation taken on the line A—A of Fig. 1, through the center of the live-roll adjusting mechanism. This view also shows, diagrammatically, the method 40 of driving the upper and lower live-rolls. Fig. 7 is a detail front elevation of the cutter-carrier, showing the means used for adjusting the cutters vertically and transversely. Fig. 8 is a detail plan view of the 45 cutter-carrier shown in Fig. 7. Fig. 9 is a detail elevation, partly in section, of the trip-rolls and housing. Fig. 10 is a dia- 50

grammatic illustration of the method employed for leaving an unchamfered intermediate attaching-space on the cross-arms. 55

Like numerals of reference indicate similar parts throughout the several views.

Referring to the drawings, 1 indicates the main frame or table of my cross-arm shaper and 2 the legs or supporting frame for said 60 table 1. A slight reduction in the height of the table is indicated at 1^a—its purpose will be indicated hereinafter. Up cast guide flanges 3 are provided along the front edge of the table 1 and form a part thereof. Adjustable rear guide-strips 4 are attached to the surface of table 1 by T-bolts 5 in T-slots 6 and are so disposed as to lie parallel to 65 guide flanges 3, thus forming a transverse channel adapted to receive and guide a 70 cross-arm 7 from one side of the machine to the other over the surface of the table 1.

Sprockets 8 and 9 carrying conveyer chains 10 and 11 running in grooves 10^a and 11^a respectively, in the table 1, are mounted 75 respectively on shafts 12 and 13 rotatably held in their respective bearings 14 and 15 as illustrated in Fig. 2. In order that the cross-arm may be delivered to the shaper at a speed conforming to the peripheral speed 80

of the live rolls it becomes necessary that the conveyer sprocket shaft 12 be geared with said live rolls, all of which receive their motive power from one common drive shaft. An initial drive shaft 16 carrying a drive 85 pulley 17 is horizontally disposed beneath and parallel with the table 1, and is revolvably held in bearings 18 attached to the supporting frames 2. A secondary drive shaft 19, carrying bevel pinions 20 and 21 and a 90 bevel gear 22, is vertically disposed above and with its axis perpendicular to the initial drive shaft 16 and is revolvably mounted in bearings 23, 24 and 25 carried by the machine. Bearing 23 is carried by a bridge 95 member 26 connecting the supporting frames 2. Said gear 22 is rigidly mounted on the secondary drive shaft 19 below and adjacent to bearing 23 and meshes with a bevel pinion 27 mounted on the initial drive-shaft 16, thereby imparting rotary motion to said secondary drive-shaft 19 when power is applied to the initial drive-shaft 16 through the medium of its drive pulley 17, 100

which may be connected by means of a belt with an engine or other source of motive power.

Bevel pinion 20 is keyed onto the secondary drive-shaft 19 and meshes with and drives a bevel gear 28 rigidly mounted on a shaft 29 carrying a spur gear 30. Shaft 29 is horizontally disposed and revolvably mounted in bearing 31 carried by the table 10 and bearing 32 carried by a bearing bracket 33 mounted on the supporting frames 2.

Three live rolls 34, which hereinafter will be designated as the lower live rolls, are mounted on and rotate with shafts 35 carrying spur gears 36, 37 and 38. A spur gear idler 39, mounted on shaft 40, is also provided. Shafts 35 and 40 are revolvably mounted in bearings 41 carried by bearing bracket 33 and bearings 42 carried by the main frame and are so disposed relatively as to permit gears 37 and 38 to mesh with and be driven by gear 30,—the spur gear idler 39 meshing with and being driven by gear 35, and meshing with and driving gear 36. Referring to Fig. 6, it will be seen that this arrangement of gears will impart to the lower live rolls a rotary motion of the traclockwise direction as viewed from the front of the machine. As the lower live rolls are to be used as conveying rolls it is desirable that their connecting gears be so proportioned as to permit of a uniform peripheral speed for said rolls. As previously stated, it is preferred that the conveyer 35 sprocket wheel 8 have the same peripheral speed as the lower live rolls, therefore, I provide a sprocket wheel 43 mounted on shaft 12 and a sprocket wheel 44 mounted on shaft 35 and a connecting sprocket chain 45. Although the foregoing arrangement of lower live rolls and conveyer will carry the cross arms 7 over the surface of the table 1, these alone will be insufficient to properly hold the cross arms in position for chamfering; therefore, I provide two upper live rolls 46 mounted on shafts 47 rotatively held in bearings 48 carried by an adjusting frame 49. Adjusting-frame supporting rods 50 are perpendicularly attached to the rear edge of table 1 and to bearing bracket 33 and are braced one against another by a cover plate 51 to which the upper ends of said supporting rods are attached. This plate 51 also carries the hereinafter mentioned bearing 52 for shaft 19. Supporting rods 50 are threaded to receive nuts 52 having flanges 53 adapted to carry the adjusting frame 49. Vertical adjustment of the adjusting frame 49 is accomplished by rotating the adjusting nuts 52 and in order that these may be operated in unison they are provided with sprocket wheels 54 attached by means of set screws 55 and connected by a sprocket chain 56 which also passes over a drive sprocket wheel 57, mounted on a crank shaft 58 held

rotatively in bearings 59 on adjusting frame 49 and operated by a crank 60.

Shafts 47 carry spur gears 61 which mesh with and are driven by a spur gear 62 mounted on a shaft 63 rotatively held in bearings 64 on adjusting frame 49. Shaft 63 carries a bevel gear 65 which meshes with the aforementioned bevel pinion 21. The bevel pinion 21 is slidably mounted on the secondary drive shaft 19 and is caused to rotate therewith by a feather 66 which slides in a featherway 67. This method of mounting the bevel pinion 21 is necessary to permit vertical adjustment of the adjusting frame. Bearing 24 which is attached to the adjusting frame 49 controls the vertical movement of said bevel pinion 21 which rests upon it.

The upper live rolls and their drive-gears just described are required to be of the proper dimensions to procure the same peripheral speed for the upper live rolls as for the lower live rolls.

After passing between the upper and lower live rolls the chamfered cross arms 7 pass onto a removing conveyer chain 11 having attachments 68 adapted to carry the cross arms along a conveyer trough 69 to any desired location. To prevent the chain attachments 68 touching the cross arms 7 until they have passed entirely clear of the upper live rolls 46, table 1 is depressed at 1^a as shown in Fig. 2.

The foregoing description covers the cross-arm conveying mechanism which may be altered in many ways as for instance, by reducing or increasing the number of live rolls or by altering the arrangement of gears or conveyers.

I shall now describe the chamfering mechanism and the means for automatically controlling it.

Chamfering cutter blades 70 are bolted onto two sides of cutter heads 71 by means of T-bolts 72 held in T-slots 73. The cutter heads 71 are rigidly mounted on vertically disposed cutter-spindles 74 rotatively held in boxes 75 adjustably attached to transversely disposed brackets 76 of a rocking-frame 77 having trunnions 78 vertically disposed at its upper and lower extremities. The trunnions 78 of the rocking frame 77 are pivotally mounted in upper and lower bearings 79 and 80 respectively. Bearing 79 is carried by the cover plate 5 and bearing 80 is carried by a bracket 81 attached to the supporting frames 2. Lower pivot boxes 82 are adjustably attached to a transverse bracket 83 attached to the rocking frame 77 and are provided with bottom adjusting screws 84 having hand-wheels 85. Adjusting screws 84 are adapted to receive the lower ends of spindles 74 which rest upon wearing disks 86. In order to hold screws 84 against undue rotation, boxes 82 are slotted at 87 and provided with clamp screws 130

88 adapted to hold the adjusting screws 84 rigidly in place after adjustment. For rotating the cutter blades, pulleys 89 are slidably mounted on spindles 74 and rotate them 5 by means of feathers 90 slidably held in featherways 91 in spindles 74.

Transverse adjustment of boxes 75 and 82 on their respective brackets 76 and 83 is accomplished by means of T-bolts 92 held in 10 slots 93. This transverse adjustment of the cutter spindles is necessary in order to decrease or increase the length of the unchamfered space.

The driving mechanism for operating the 15 cutter blades consists of bevel gears 94 mounted on the initial drive shaft 16, and which are held in mesh with and drive bevel pinions 95 which are mounted on vertical shafts 96 disposed above and perpendicular 20 to the axis of the initial drive shaft 16. Shafts 96 are mounted rotatively in upper and lower bearings 97 and carry drive pulleys 98 disposed between said upper and lower bearings 97. Motive power from pulleys 98 is transmitted to pulleys 89 on the 25 cutter spindles through the medium of belts 99 which are kept taut by means of idler pulleys 100 over which they pass. Said idler pulleys 100 are rotatively mounted in 30 adjustable housings 101 carried on grooved transversely disposed guide bars 102 and are adjusted by means of nuts 103 on adjusting screws 103, which pass through lugs 104 carried by the machine frame, and are 35 attached to the housings 101.

In the manufacture of cross-arms it is necessary to chamfer the weather edge as shown in Figs. 4 and 5 at 7^a leaving an unchamfered portion, as at 7^b. I accomplish this chamfering automatically in my 40 cross-arm shaper by means of a trip mechanism adapted to hold the left hand cutter in working position as shown diagrammatically at 70^a in Fig. 10 and at the same time holding the right hand cutter in an inoperative 45 position, as at 70^b, until the chamfer 7^a has reached a desired and predetermined point at which the unchamfered portion starts. The trip mechanism now reverses 50 the positions of the cutters placing the right hand cutter in operative position as shown at 70^c and removing the left hand cutter to an inoperative position, as at 70^d, thus leaving an unchamfered portion, as shown at 7^e.

The automatic trip mechanism is operated by means of a trip roller 106, journaled on a shaft 107 held between the forked ends of a trip bracket 108 having attached 55 to it a trip lever 109. The trip bracket 108 is pivotally mounted on a shaft 110 carrying a hold-down roll 111 and held in adjusting bracket 112 pivotally mounted in a housing or case 113, on a rod 114. In order to accommodate the various thick-

nesses of cross arms the adjusting bracket 65 112 may be adjusted by means of screw 115 which is provided with a lock nut 116 and is held by a bracket 117 attached to the housing 113, a lock bar 120 is provided for holding up the roll 111 and is fastened by screws 70 121, an adjustment for thick cross arms being indicated by dotted lines at 111^a.

To place the unchamfered space centrally on a cross arm it becomes necessary to move the trip roll along the table to the proper 75 position. To facilitate the adjustment of the trip-roll as just mentioned the housing is provided with gibbs 118 engaging the edge of the table 1 and adapted to grip said table edge by means of screws 119.

Trip bar 109 carries an adjustable slide block 122 from which depends a swivel joint 123 connecting the slide block with a vertical connecting rod 124, which is also connected by means of another swivel joint 125 with a short operating arm 126 mounted on an operating shaft 127 journaled in bearings 128 and 129 attached respectively to the floor and to the machine supporting frame 2. A weight lever 130 carrying a 90 weight 131 is mounted on the operating shaft 127 diametrically opposite the arm 126 and tends to hold the trip roll 106 in a down position. A rocking frame operating arm 132 is mounted on the operating shaft 95 127 nearly opposite the nearest cutter and is connected with a lug 133 on bracket 83 by connecting rod 135.

It is obvious now that a cross arm being 100 conveyed through the machine would have its weather edge chamfered by the left hand cutter until the cross arm has reached a point where the trip roll would be allowed to drop, whereupon the trip mechanism would cause the left hand cutter to recede and the right hand cutter would finish 105 chamfering the remainder of the cross-arm, leaving an intervening unchamfered space.

Although I have described my invention 110 as a machine adapted to chamfer cross-arms, I do not desire to limit the range and operation of the machine to that one product, but on the contrary desire to include variously chamfered and finished articles of 115 wood in which the chamfering or other finish may be intermittent as for instance stair-newels, table legs and balusters. By altering the shape of the cutter blocks, intermittent grooves or flutes may be produced as well as various other shapes, and molding, 120 etc.

What I claim, is—

1. A wood-working machine comprising 125 in combination a conveyer, a pair of cutters mounted rotatively upon cutter-carrying spindles carried in a pivotally mounted rocking frame, means for adjusting the height of said cutter carrying spindles,

means for adjusting and setting said spindles with reference to the pivotal center of the rocking-frame, and means actuated by the passage of said wood-products to rock 5 said rocking-frame so as to introduce first one and then the other of said cutters into operative contact with said wood products.

2. In a wood-working machine of the character described a vertically disposed 10 rocking frame, having transverse brackets provided with horizontally disposed slots, and provided with an upper and a lower trunnion by means of which the frame is pivotally mounted in the machine, bearings 15 adjustably attached to the brackets by means of bolts passing through the slots, two cutter carrying spindles revolvably mounted in the bearings so as to be in coaxial alinement with the trunnions and disposed one at each 20 side of the axis of said trunnions, a pulley slidably mounted on and feather-keyed to each of said spindles, and an adjusting screw carried by the lower bearing of each spindle and adapted to vertically adjust the 25 spindle without altering the height of the pulley thereon.

3. In a machine of the character referred to, in combination, a rocking frame, revolving cutters mounted in said rocking frame 30 at opposite sides of the axis thereof, means for driving said cutters, a guideway adjacent said cutters and extending transversely of the axis of said rocking frame, and means for rocking said rocking frame 35 to alternately move said cutters into the operating position, said means being controlled by the material passing along said guideway.

4. In a machine of the character referred 40 to, a rocking frame, revolving cutters mounted in said rocking frame at opposite sides of the axis thereof, means for driving said cutters in opposite directions, a guideway adjacent said cutters and extending 45 transversely of the axis of said rocking frame, and means for rocking said rocking frame to alternately move said cutters into operating position, said means being auto-

matically controlled by the movement of the material passing along said guideway, 50 substantially as described.

5. In a machine of the character described a vertically disposed rocking frame pivotally mounted in the machine upon a vertical axis, bearings carried by said rocking 55 frame, cutter carrying spindles rotatively and vertically mounted in said bearings, pulleys slidably mounted on the spindles and means for vertically adjusting the spindles without altering the height of the pulleys, in combination with a rocking-frame 60 actuating mechanism comprising a housing, a U shaped frame pivotally mounted in the housing on a horizontal axis, a roller carried horizontally by the U shaped frame, a 65 tilting frame pivotally carried by U shaped frame, a roller carried horizontally by the tilting frame, an arm carried by the tilting frame, means for limiting the movement of the U shaped frame and means connecting 70 the arm of the tilting frame with the aforementioned rocking-frame so that any vertical movement of the rollers and arm will tend to rock the rocking-frame as described.

6. In a machine of the character described 75 and having a cutter-carrying rocking-frame, a rocking-frame actuating mechanism comprising a housing, a U shaped frame pivotally mounted in the housing on a horizontal axis, a roller carried horizontally by the U shaped frame, a tilting frame pivotally carried by the U shaped frame, a 80 roller carried horizontally by the tilting frame, an arm carried by the tilting frame, means for limiting the movement of the U 85 shaped frame and means connecting the arm of the tilting frame with the aforementioned rocking-frame so that any vertical movement of the rollers and arm will tend to rock the rocking-frame as described. 90

In testimony whereof I affix my signature in the presence of two witnesses.

ETHELBERT L. BARNES.
